UNITED STATES PATENT OFFICE

150,317

DESIGN FOR A VISUAL EDUCATIONAL PROJECTOR

Hudson B. Roysher, Los Angeles, Calif., assignor
to Ward Hickok, Beverly Hills, Calif.

Application February 14, 1948, Serial No. 144,499

Term of patent 14 years

(Cl. D61—1)

To all whom it may concern:

Be it known that I, Hudson B. Roysher, a citizen of the United States, residing at Los Angeles, in the county of Los Angeles and State of California, have invented a new, original, and ornamental Design for a Visual Educational Projector; of which the following is a specification, reference being had to the accompanying drawing, forming part thereof.

The drawing illustrates a visual educational projector embodying my new design in which:

Fig. 1 is a perspective view of the projector;

Fig. 2 is a side elevational view of the projector;

Fig. 3 is a front elevational view of the projector; and

Fig. 4 is a rear elevational view of the projector.

I claim:

The ornamental design for a visual educational projector, as shown.

HUDSON B. ROYSHER.
